VENDING STAND

Filed Sept. 24, 1928

INVENTOR.

Anthony Soucie
BY Miller, Boyken & Bried
ATTORNEYS.

UNITED STATES PATENT OFFICE.

ANTHONY SOUCIE, OF OAKLAND, CALIFORNIA.

DESIGN FOR A VENDING STAND.

Application filed September 24, 1928. Serial No. 28,264. Term of patent 7 years.

To all whom it may concern:

Be it known that I, ANTHONY SOUCIE, a citizen of the Dominion of Canada, residing at Oakland, county of Alameda, and State of California, have invented a new, original, and ornamental Design for a Vending Stand, of which the following is a specification.

The figure is a perspective view of the vending stand showing my new design.

I claim:

The ornamental design for a vending stand as shown.

ANTHONY SOUCIE.
